DESIGN FOR A BOTTLE

Rudolph Liska, Jr., Chicago, Ill.

Application June 21, 1943, Serial No. 110,499

Term of patent 14 years

(Cl. D58—8)

To all whom it may concern:

Be it known that I, Rudolph Liska, Jr., a citizen of the United States and resident of Chicago, in the county of Cook and State of Illinois, have invented a new, original, and ornamental Design for a Bottle, of which the following is a specification, reference being had to the accompanying drawing, forming a part thereof.

In the drawing, the figure is a perspective view of a bottle, showing my new design.

This bottle is generally round throughout its height and the opposite side is substantially the same as the side shown.

I claim:

The ornamental design for a bottle, as shown and described.

RUDOLPH LISKA, JR.
